COMBINED BATHROOM SCALE SUPPORT STAND
AND RECORD SHEET CONTAINER OR SIMILAR ARTICLE

Louis Cole, 2130 Lincoln Park West, Apt. 14 N.,
Chicago, Ill. 60614

Filed Feb. 24, 1967, Ser. No. 5,939

Term of patent 14 years

(Cl. D33—3)

FIG. 2

FIGURE 1 is a front view of a combined bathroom scale support stand and record sheet container or similar article, showing my design;

FIGURE 8 is a side view of FIGURE 7 with the lower portion of the article omitted for convenience of illustration;

FIGURE 9 is a view similar to FIGURE 8, with the inside cover open, with the lower portion of the article omitted for convenience of illustration and

I claim:

The ornamental design for a combined bathroom scale support stand and record sheet container or similar article, as shown.
